CARTRIDGE LOADING MACHINE
Joseph M. Agnese, 2770 Greenwich St.,
San Francisco, Calif.
Filed Jan. 3, 1961, Ser. No. 80,110
7 Claims. (Cl. 86—23)

This invention relates to a cartridge loading machine of the type adapted for use in reloading small arms cartridge cases.

The cartridge loading machine embodying the present invention is primarily intended for use by marksmen, hunters and others who are desirous of conveniently and inexpensively reloading discharged cartridges. The machine functions automatically to release and deposit a predetermined explosive charge of powder into each of a number of empty cartridge cases as the latter are brought successively into a loading position beneath a powder holding tube. The machine also functions automatically to position a bullet in the open end of each of a number of powder containing cartridge cases as the latter are successively brought into a receiving position beneath a supply magazine holding a number of similar bullets. The machine is adapted to be operated by a hand lever or other suitable means to automatically load the empty cartridge cases with identical charges of explosive powder and with bullets of substantially the same shape and size. Various adjustments may be made with respect to certain parts of the machine to permit the empty cartridge cases to be loaded with varying charges of explosive powder and also to adapt the machine for use with bullets and cartridges of different calibers.

The primary object of my invention is to provide a novel cartridge loading machine having automatic means for loading empty cartridge cases with uniform loads of explosive powder and for automatically securing bullets in the open ends of such cases.

Another object of my invention is to provide a novel cartridge loading machine of the kind characterized, having an adjustable powder holding tube which may be lengthened or shortened to increase or decrease its capacity whereby an operator may selectively determine with precision and accuracy the amount of explosive powder loaded into each of a number of cartridge cases.

Another object of my invention is to provide a novel cartridge loading machine having various adjustable features which make it possible to adapt the machine for use with different caliber cartridges and projectiles or bullets.

Still another object of my invention is to provide a novel cartridge loading machine of the kind characterized, having automatic control means for delivering a predetermined charge of explosive powder to an empty cartridge case at approximately the same time as a bullet is delivered to another cartridge case which had been previously supplied with an explosive charge.

Still another object of my invention is to provide a cartridge loading machine which, by reason of its novel construction and design, is adapted to be operated to reload the cartridge cases at a considerable saving of time and expense over methods now in use.

Other and further objects of my invention will be pointed out hereinafter or will be indicated in the appended claims or will be obvious to one skilled in the art upon an understanding of the present disclosure. For the purpose of this application, I have elected to show herein certain details of a cartridge loading machine which is representative of my invention; it is to be understood, however, that the embodiment of my invention herein shown and described is for purposes of

2

illustration only, and that it is not to be regarded as exhaustive of the variations of the invention in the art.

In the accompanying drawings:

FIG. 1 is a rear elevational view of a cartridge loading machine embodying my invention, showing the operating lever in an inoperative raised position;

FIG. 2 is a side view of the machine;

FIG. 3 is a perspective view of the container for holding a supply of explosive powder, showing the delivery tube and control means associated therewith;

FIG. 4 is a front elevational view of the machine, showing the operating lever in a downwardly adjusted position;

FIG. 5 is a vertical sectional view, on an enlarged scale, of a portion of the powder holding means, showing an empty cartridge case in position for movement into a receiving chamber preparatory to its being loaded with an explosive charge;

FIG. 6 is a similar view of the powder holding means, showing the cartridge case in position for receiving a charge of explosive powder;

FIG. 7 is a sectional view taken on the line 7—7 of FIG. 5;

FIG. 8 is a sectional view taken on the line 8—8 of FIG. 6;

FIG. 9 is a vertical sectional view, on an enlarged scale, of the bullet loading mechanism, showing a cartridge case in position for movement into engagement with a bullet supported in a tubular receiver;

FIG. 10 is a similar view of the bullet loading mechanism, showing the cartridge case after it has been raised sufficiently to receive the bullet;

FIG. 11 is a sectional view taken on the line 11—11 of FIG. 10;

FIG. 12 is a perspective view of the adjustable powder holding tube and gauge;

FIG. 13 is a vertical sectional view of the adjustable powder holding tube, showing the gauge in elevation and showing also the closure means for the lower end of the tube positioned to prevent the discharge of powder therefrom; and

FIG. 14 is a similar view showing the closure means in an open position to allow powder to enter the open end of a cartridge case arranged to receive such powder.

Referring to the drawings, the numeral 1 designates a supporting structure mounted in a fixed position on a suitable support 1a. Secured to the supporting structure is a main vertical guide post 2 and auxiliary vertical guide posts 3 and 4, all of which are preferably arranged in a common vertical plane. The posts 2 and 3 loosely extend through vertical openings in a vertical reciprocating carriage or member 5 which is cushioned near the end of its downward movement by helical compression springs 6 associated with and held against displacement by the auxiliary posts 3 and 4. The main post 2 and the auxiliary post 3 extending loosely through the vertical openings in the carriage 5 prevent any rotational or lateral movement thereof. The auxiliary post 4 is comprised of two telescopically arranged sections between which a compression spring 6 is positioned. The upper end portion of the upper tubular section of the post 4 is adapted to extend into the vertical opening of a tubular cartridge case holding socket 7 supported by the carriage 5 when the carriage approaches the end of its downward movement. Secured to the carriage is a bracket 8 which carries a similar cartridge holding socket 9 that is preferably positioned at about ninety degrees (90°) from the socket 7. Both of the sockets 7 and 9 are formed in the usual manner with entry slots and semi-circular grooves which are adapted to receive the peripheral edges of the base portions of cartridge cases. C. The socket 7 and the telescopic post 4, while em-

ployed in connection with means for applying a percussion cap to a cartridge case are not considered a part of the present invention.

Pivotedly connected at a point intermediate its ends by a pivot pin 10 to the stationary supporting structure 1 is a hand lever 11. Secured by rivets 12 or the like to an end of the hand lever 11 and also connected pivotedly to the pin 10, are identical links 13 of somewhat triangular shape. The links 13 are pivotedly connected at their apexes by rivets 14 or the like to the lower ends of identical links 15 which are connected at their upper ends by a pivot pin 16 to the carriage 5. The horizontal axis of the pin 10, the rivets 12 and the rivets 14 are arranged in triangular formation so that by depressing the lever 11, the triangular links 13 actuate the links 15 upwardly to raise the carriage 5. The carriage is lowered when the hand lever 11 is actuated upward y.

Supported on the upper end of the main post 2 is a stationary platform 17 having vertical threaded openings 18 and 19 which are positioned directly above the cartridge holding sockets 7 and 9, respectively. Screwed into the opening 18 is a cartridge receiving tube 20 which is adapted to be vertically adjusted. A lock nut 21 adjustably engaging with the external threads of the tube 20 bears against the stationary platform to hold the tube against rotation and displacement. Supported on and suitably secured to the platform is a substantially vertical rod 22 which is threaded at its upper and lower ends to provide means at its lower end for the attachment of adjustable nuts used in securing the rod to the platform and to provide means at its upper end for the attachment of nuts used in adjustably securing a bracket 23 to the rods. Supported for swinging movement on the bracket 23 is a connecting member 24 which is attached at its lower end to a sleeve 25 through which an upright tubular bullet holder or magazine 26 extends. The sleeve is adjustably secured to the tubular bullet magazine by a set screw 27. Since the connecting member 24 is mounted for swinging movement on the bracket 23, the bullet magazine is also adapted to swing back and forth from a substantially vertical position with its lower outlet end in vertical alignment with the cartridge receiving tube 20 as shown in FIG. 9 to a slightly inclined position with its outlet end positioned to one side of the cartridge receiving tube as shown in FIG. 10. The bullet holder or magazine 26, in the form illustrated, has a bore adapted to hold a considerable number of bullets or projectiles B which move by gravity through the magazine to its outlet end.

Upon movement in a downward direction of the hand lever 11, a cartridge supported on the socket 7 is carried upwardly into the cartridge receiving tube 20 at the same time the lower outlet end of the bullet magazine 26 is moved outwardly from a position registering with such tube, wherein it had previously delivered a bullet to the upper end of such tube. The upward movement of the hand lever 11 lowers the cartridge case with a bullet C secured thereto at the same time the discharge end of the bullet magazine 26 is moved into registry with the cartridge receiving tube 20, preparatory to the delivery of another bullet to such tube. The means synchronizing the movement of the bullet magazine in accordance with the movement of the hand lever, as well as the controls for the bullets delivered to the cartridge receiving tube 20 will be presently described. Secured to the carriage 5 is an upright member 28 to which one end of a bar 29 is connected as by a pivot pin or bolt 30, the other end of such bar being pivotedly connected as by a pivot pin or screw 31 to a nut 32 which is secured within a tubular member 33 having two depending opposed flanges 34 thereon. Secured at one of its ends to the bar 29 is an angular bar 29a which is pivotedly connected as by a pivot pin 31a to the nut 32 and the tubular member 33. Connecting the pivot pins 31 and 31a with the lower end of the tubular bullet

magazine 26 are links 35, 35, the said links being laterally slotted at corresponding ends and connected at such slotted ends to pivot screws or pins 36, 36 which are secured to the lower end of the bullet magazine. The lower ends of the depending flanges 34 of the tubular member 33 are pivotedly connected as at 37 to the cartridge receiving tube 20. Thus, when the hand lever 11 is depressed, the lower end of the bullet magazine 26 is moved outwardly from a position registering with the cartridge receiving tube 20, and when the hand lever is moved upwardly, the lower end of the bullet magazine is actuated reversely to a position wherein its bore is again in registry with the bore of the tube 20.

So as to control the bullets B moving downwardly in the magazine 26 and into the cartridge receiving tube 20, suitable means is provided to effectuate the desired results. The bullet magazine 26 is provided with a substantially horizontal slot 38 which is positioned about the length of a bullet B from its lower end. Suitably secured at its upper end to the bullet magazine 26 as at 39, is a depending resilient member in the form of a flat spring 40, having a first bullet intercepting and holding member 41, secured thereto as by a bolt and nut combination 42. The first bullet intercepting member 41 is adapted to enter the slot 38 and intercept and temporarily support the particular bullet B then positioned above such slot in the lower end of the bullet magazine 26, this being accomplished when the magazine is positioned with its outlet end in registry with the opening in the cartridge receiving tube 20 and the carriage 5 is in a lowered position with the hand lever 11 elevated. Secured to and carried at the lower end of the depending resilient member 40 is a second bullet intercepting and holding member 42' which is arranged to project inwardly at a point below the outlet end of the bullet magazine 26 and thereby intercept and temporarily support the particular bullet then positioned directly below the slot 38 when the magazine is in an inclined position with its outlet end spaced laterally from the cartridge receiving tube 20. Thus, when the bullet magazine is in an inclined position with its outlet end no longer in registry with the cartridge receiving tube, the bullet intercepting members 41 and 42' are positioned, respectively, to release the particular bullet then directly above the slot 38 and support the bullet directly below such slot, respectively. Secured to the lower end of the bullet magazine 26 is a third bullet intercepting and holding member 43 which is arranged to extend inwardly below the stationary platform 17 and beneath the vertical opening 18 to intercept and support a bullet then in the cartridge receiving tube 20, this being accomplished when the bullet magazine 26 is in its vertical position with its outlet end aligned with the opening in the cartridge receiving tube 20. As the hand lever 11 is elevated and the lower outlet end of the bullet magazine moves inwardly toward a position in alignment with the cartridge tube 20, the second bullet intercepting and holding member 42' is carried into engagement with the cartridge receiving tube 20 and upon completion of such inward movement of the lower end of the bullet magazine, the depending resilient member flexes and the second bullet intercepting and holding member 42' is withdrawn from its bullet supporting position, thereby allowing the bullet then engaging with and supported by such second bullet holding member to drop into the cartridge receiving tube 20 to be supported by the third bullet intercepting and holding member 43. Simultaneously, the first bullet holding member 41 is moved into the slot 38, thereby intercepting and holding the lower bullet then in the magazine 26. The bullet then supported in the cartridge receiving tube 20 by the member 43 is in position for engagement by a cartridge case C which is then held in the socket 7 carried by the carriage 5. The cartridge receiving tube 20 is formed internally with annular converging shoulders 20a which

are adapted to engage with similar converging shoulders provided in the usual manner on the cartridge case, thereby limiting the upward movement of the latter in the said cartridge tube.

Carried by the nut 32 is an adjustable screw 44 which, when the carriage 5 is actuated upwardly, is moved from an inclined position to a position in vertical alignment with the longitudinal axis of the cartridge receiving tube where its lower end is adapted to intercept the upper pointed end of the bullet then in the cartridge receiving tube 20. As the hand lever 11 is depressed, the carriage 5 with a powder loaded cartridge case C supported thereon is moved upwardly, thereby causing such cartridge case to enter and move upwardly in the cartridge receiving tube 20. At the same time the lower outlet end of the bullet magazine 26 is swung outwardly to a position wherein it no longer registers with the opening in the cartridge receiving tube 20. With the pressure being removed by the second bullet intercepting and holding member 42' disengaging from the tube 20, the resilient member 40 resumes its normal straight position, thereby causing the first and second bullet intercepting members 41 and 42' to again become positioned so as to intercept and temporarily support bullets dropping downwardly in the magazine 26, as shown in FIG. 10. Also, at the same time, and as the powder loaded cartridge case C is entering the lower end of the tube 20, the third bullet intercepting and holding member 43 is withdrawn from a supporting position, thereby allowing the cartridge case to enter the tube 20 and engage with the bullet then in the lower end of such tube. The bullet and the upper restricted opening in the upper end portion of the cartridge case are nearly the same in diameter, but the bullet being slightly larger will be carried upwardly with the cartridge case until it intercepts the lower end of the then vertical screw 44 which prevents any further upward movement of such bullet. The further upward movement of the carriage 5 to the upper extremity of its upward reciprocating movement will raise the cartridge case to a position in which the bullet will have been forced into the open end of the cartridge case, as shown in FIG. 10. The reverse upward movement of the hand lever 11 will lower the carriage 5 and retract the loaded cartridge case with the bullet secured thereto. The downward movement of the carriage causes the lower end of the bullet magazine 26 to swing inwardly and again resume a position in registry with the cartridge receiving tube 20. It is to be noted that as the lower end of the magazine swings inwardly the screw 44 moves outwardly from the said tube to allow the magazine to assume a position whereby another bullet may be delivered to the cartridge receiving tube. As the lower end of the bullet magazine moves inwardly to its bullet discharging position, the third bullet intercepting and holding member 43 is carried to a position wherein it is adapted to intercept a bullet released by the second bullet intercepting and holding member 42'. Simultaneously, the first bullet intercepting and holding member 41 is carried along with the member 42' to a bullet releasing position in which another bullet may drop from the magazine into the cartridge tube 20.

The present invention contemplates the use of synchronizing means whereby a cartridge case is loaded with a charge of explosive powder at the same time a bullet is being inserted into and attached to another cartridge. Mounted on the stationary platform 17 in vertical alignment with the cartridge holding socket 9 carried by the carriage 5 is a vertical cartridge receiving tube 45 which is screwed into the threaded opening 19 in the platform. The tube 45 is adapted to receive a cartridge C when the carriage 5 is raised upwardly; and inwardly converging annular shoulders 45a on such tube are adapted to engage with similar shoulders on the cartridge case to limit the upward movement of such case. Supported on an upright stationary post 46 secured to the platform 17 is a

block 47 which has a vertical opening 47a arranged in communication with the axial opening extending through the cartridge tube 45. Also supported by the post 46 in vertically spaced relation to the block 47 is a plate or block 48 which has a vertical opening 48a arranged in laterally spaced relation to a vertical axis extending through the openings 19 and 47a. Mounted between and in contact with the blocks 47 and 48, respectively, are vertically spaced valve plates 49 and 50 which are mounted for simultaneous swinging movement about a vertical axis extending through the stationary post 46. The valve plate 49 has a vertical opening 49a arranged in vertical alignment with a similar vertical opening 50a in the valve plate 50. The opening 49a is adapted to register with the vertical opening 47a, and similarly, the opening 50a is adapted to register with the opening 48a. Secured to and extending between the valve plates 49 and 50 is a powder holding tube or container 51 which is preferably transparent. The powder tube 51 is also preferably telescopic in construction consisting of two or more sections arranged telescopically for convenient adjustment to lengthen or shorten the tube for the purpose of changing its capacity so a smaller or larger load of powder may be received and held thereby. The axial opening in the powder tube 51 is in direct communication with the vertical openings 49a and 50a of the valve plates 49 and 50, respectively. The powder tube 51 is capable of being lengthened or shortened by suitably adjusting the relative spaced positions of the blocks 47 and 48 on the post 46 and also accordingly adjusting the valve plates 49 and 50 which respectively engage with the blocks. The powder tube may also have a fixed length so it will contain a predetermined charge of explosive powder. It is to be noted that the openings 49a and 50a in the valve plates 49 and 50, respectively, are so arranged that when 50a is in registry with the opening 48a, the opening 49a will not be in registry with the opening 47a and vice versa. Supported on the upper block 48 and suitably secured thereto is a powder delivery tube 52 which supports a powder container 53 at its upper end. Powder supplied from the container 53 is adapted to flow by gravity into the powder tube 51 when the valve plate 49 is positioned with its opening 49a in registry with the opening 48a of the block 48. A flat slide valve 54 extending through an enlarged lower portion 52a on the powder delivery tube 52 is provided in the usual manner with a suitable opening, which when such slide valve opening is in registry with the longitudinal opening in the powder delivery tube, will allow powder to flow downwardly into the powder tube 51. The slide valve 54 is manually operated to permit a suitable amount of powder to enter the powder tube 51, and the latter being preferably transparent makes it possible for an operator to observe the flow into and the contents of the powder tube.

Pivoted mounted as at 55 on an upright standard 56 supported on the post 46 is lever 57 which carries a forked member 58 at its lower end. The forked member slidably extends into a guide slot in the block 47. A fixed pin or projecting member 59 rigidly secured to the valve plate 49 extends horizontally between the forks of the forked member 58 and when the lever 57 pivots back and forth about the pivot 55, the valve plates 49 and 50 are pivotally moved to positions wherein the openings 47a and 48a are alternately opened and closed. The pivotal movement of the lever 57 is accomplished by means about to be described. Secured as by the bolt 30 to the upright member 28, which is connected to the carriage 5, is an elongated upstanding extension 60 which has an inclined track 60a on its upper end. Secured to the upper end of the lever 57 is a projecting screw, pin or other suitable device which constitutes a pressure applying member 61 that engages with and is adapted to travel over the track 60a. When the hand lever 11 is elevated and the carriage 5 is in a lowered position, the member 61 is positioned at the upper end of the inclined

track 60a and the powder tube 51 is positioned to receive powder from the delivery tube 52. A coil tension spring 62, connected at its ends to the upper end of the lever 57 and the stationary upright standard 56, is adapted to return the lever and the various elements actuated thereby to their respective positions as shown in FIG. 1. As the hand lever 11 is depressed and the carriage is elevated, the inclined track 60a, moving upwardly against the member 61 actuates the lever 57 so as to move the powder tube 51 to a position wherein its contents may flow through the opening 47a in the block 47 and into the cartridge receiving tube 45, and thence into the open end of the cartridge C then supported inside the latter. During such movement the valve plate 50 is carried from a position in which its opening 50a communicates with the opening 48a of the block 48 to a position in which such opening 48a is closed, thereby preventing powder from escaping from the powder delivery tube 52. The upward movement of the hand lever 11 lowers the carriage 5 and permits the cartridge C which now has a powder charge therein to be manually removed from the socket 9 and transferred to the socket 7 preparatory to the connection of a bullet, as previously described. The powder tube 51 is simultaneously returned to its powder receiving position when the carriage is lowered to permit the removal of the carriage from its socket 9.

As shown in FIGS. 12, 13 and 14, a detached arrangement may be used to load a cartridge with a predetermined charge of powder. A suitable support 70 comprising a horizontal member 70a and a connected upright member 70b is adapted to be suitably supported, as by a vise or other means. Secured at its lower end to 70a is a stationary vertical pivot post 71 which has an elongated tube 72 loosely rotatable and supported thereby, such tube 72 being externally threaded as at 72a. Mounted for vertical adjustment on the tube 72 is a sleeve 73 which has a horizontal closure plate 74 secured to its lower end. Secured to the lower end of the tube 72 is an adjustable valve plate 75 having a valve opening 76 which is adapted to register with an outlet opening 77 in the horizontal member 70a of the support. Supported on and carried by the valve plate 75 is the lower section of a telescopic transparent powder holding tube or container 78. Adjustably mounted for vertical adjustment on the tube 72 is a slideable sleeve 79 which is adapted to be secured as by a set screw 80 to such tube. Secured to the upper end of the sleeve 79 is a plate 81 having a vertical opening 82 which is in registry with the opening in the upper section of the powder holding tube 78, the said upper section being suitably secured to the plate 81. After the set screw 80 has been turned to permit the upward or downward adjustment of the sleeve 79 on the tube 72, the length of the powder tube 78 may be accordingly adjusted to increase or decrease its capacity. A vertically adjustable upper nut 79a engaging with the threads 72a of the tube 72 is adapted to support the sleeve 79 and the plate 81 when the set screw 80 is released from engagement with the said tube to permit the lateral swinging adjustment of the powder holding tube 78. A lower nut 75a engaging with the threads 72a of the tube 72 is adapted to engage with the valve plate 75 to prevent the turning of the tube about the pivot post 71. A linear measure 83 provides a gauge for use in determining the correct amount of powder to be admitted to the tube 78. When the valve plate 75 is positioned with its valve opening 76 closed, the powder tube 78 may be filled by means of a funnel or other device after the closure plate 74 has first been adjusted upwardly and secured against downward displacement by a set screw 73a carried by the sleeve 73. The outlet opening 77 in 70a is adapted to receive the upper end portion of a cartridge C, which may be loaded with a charge of powder after the powder tube 78 has been adjusted to a position permitting its contents to flow through the said opening. It is to be noted that when the powder tube 78 has

been adjusted to a suitable length, it will not be possible to overload a cartridge case with an excessive charge of powder.

It is to be noted that the machine is adapted to be adjusted to accommodate cartridge cases and bullets of different calibers and sizes as well as to permit such cartridge cases to be loaded with different amounts of explosive powder.

What I claim is:

1. In a cartridge loading machine having a supporting structure, a vertical reciprocable carriage mounted on the supporting structure and having means for supporting an empty cartridge case in an upright position, means on the supporting structure for actuating the carriage upwardly and downwardly, a stationary cartridge tube supported on the supporting structure in a substantially vertical position and arranged to receive the cartridge case as the carriage and the cartridge case are moved upwardly, an adjustable powder holding tube supported on the supporting structure for swinging movement about a substantially vertical axis and having an outlet at its lower end arranged for communication with the opening of the cartridge tube when the powder holding tube is in a certain adjusted position, and synchronized means connecting the powder holding tube and the carriage, whereby when the carriage is moved upwardly to carry the cartridge case into the cartridge tube, the powder holding tube will be moved automatically to a position so its outlet is in communication with the cartridge tube.

2. In a cartridge loading machine, the combination set forth in claim 1 together with a powder supply container connected to the powder holding tube.

3. In a cartridge loading machine, as defined by claim 1, the powder holding tube having telescopic sections slidably arranged to increase or decrease the length of such tube.

4. In a cartridge loading machine, as defined by claim 1, the powder holding tube being transparent.

5. In a cartridge loading machine, a stationary substantially horizontal member having a vertical opening extending therethrough, such opening being adapted to receive the open end of a cartridge case, a vertical post secured to and extending above the horizontal member and arranged in spaced relation to the opening, an elongated tube rotatably mounted on the post, an adjustable valve element secured to the lower end of the tube and arranged in an overlying position with respect to the stationary horizontal member, the valve element having a valve opening adapted to register with the vertical opening in the stationary horizontal member, a vertically adjustable sleeve mounted on the tube, a vertically adjustable plate secured to the sleeve, the said vertically adjustable plate having a vertical opening arranged in vertical alignment with the valve opening, and a tubular container interposed between the valve element and the adjustable plate, the container having one end communicating with the opening in the stationary member and its other end communicating with the opening in the adjustable element.

6. In a cartridge loading machine, the combination set forth in claim 5 together with a vertically adjustable closure plate mounted adjustably on the tube and arranged to overlie the adjustable plate and close the opening in the same.

7. In a cartridge loading machine, the combination comprising a substantially horizontal stationary member having a vertical opening extending therethrough, such opening being adapted to receive the open end of a cartridge case, a vertical post secured to and extending above the horizontal member and arranged in laterally spaced relation to the opening, an elongated tube rotatably mounted on the post, an adjustable valve element secured to the lower end of the tube and arranged in an overlying position engaging with the stationary horizontal member, the valve element having a valve opening adapted to register with the opening in the stationary member when

the valve element is in one of its adjusted positions, a vertically adjustable sleeve mounted on the tube, a vertically adjustable plate secured to the sleeve, the said vertically adjustable plate having an opening arranged in vertical alignment with the valve opening, and an adjustable tubular container interposed between and secured at its ends to the valve element and the vertically adjustable plate, the container having its ends communicating with the openings in the valve element and the adjustable plate, the said tubular container comprising a plurality of telescopically arranged sections. 10
